UNITED STATES PATENT OFFICE.

MAURICE LACHMAN, OF NEW YORK, N. Y., ASSIGNOR TO UNIVERSAL ELECTRIC WELDING COMPANY, OF NEW YORK, N. Y., A CORPORATION OF NEW YORK.

METALLIC STRUCTURE.

1,090,312.

Specification of Letters Patent. Patented Mar. 17, 1914.

Application filed January 26, 1909. Serial No. 474,266.

To all whom it may concern:

Be it known that I, MAURICE LACHMAN, a citizen of the United States, and a resident of New York, in the county of New York and State of New York, have invented a certain new and useful Metallic Structure, of which the following is a specification.

My invention relates to metallic structures or fabrics such as used for reinforcement for concrete work, lathing and other purposes and comprising members crossing one another and secured together at their intersections by suitable fastenings.

The invention is particularly useful in connection with metallic structures or fabrics which are to be used for reinforcement for concrete work, such as for joining sections of metallic fabric together or for fastening the members of the fabric or structure at their points of intersection.

One of the objects of the invention is to provide the fabric in sections of convenient size so that they can be easily shipped and to provide a simple and ready means for joining the sections to each other so that the operation can be quickly and securely done by the workmen at the place it is desired to use the fabric.

Another object is to provide the members of a metallic structure with means whereby they can be readily and quickly secured together, these means being permanently located on one of the members when detached, whereby they can be shipped in bundles and can be quickly secured at their intersecting points when desired to form the fabric or structure and proper spacing attained.

A still further object is to provide a bar or wire with clips welded to it at intervals apart by means of which the bar or wire may be secured to a companion member, whereby reinforcements for use in any shaped form may be attained.

45 To these ends the invention consists in the improved metal fabric or structure herein-after described and claimed.

The invention also consists in the improved manner of joining the sections of metal fabric and further consists in the improved manner of fastening the members of a metallic structure to each other.

The invention consists still further in providing tension or similar bars or wires with

clips electrically welded thereto and provided with ears whereby they may be secured to a connecting bar or other companion member.

In the accompanying drawings, Figure 1 shows sections of metal fabric joined together in accordance with my invention. Fig. 2 is a section on the line $x-x$, Fig. 1. Fig. 3 is a plan of the connecting bar detached. Fig. 4 shows a metal fabric, on a reduced scale, the tension and distributing wires of which are fastened together in accordance with my invention. Fig. 5 is an enlarged section through a tension wire and clip before welding and illustrates the preferred method of securing the clip to the wire. Fig. 6 is a similar view after welding. Fig. 7 is a developed plan of the preferred form of clip. Fig. 8 illustrates the manner of forming the reinforcement for a concrete column.

In the various figures of the drawings, one of the members or tension wires of the fabric or structure is indicated at 1, while 2 indicates the distributing wires or companion members.

It is the usual practice in metal fabric used for concrete reinforcement to form the tension wire as a round wire or rod and the distributing wire flat and I will herein show them as such, but I do not limit myself to the same as other suitable forms might be employed without departing from the spirit of my invention. Also where the term "wire" is employed it will be understood that either a wire, rod, bar or other similar or equivalent member is meant.

3 indicates clips which in the preferred form are flat strips of metal and electrically welded to the surface of the tension wires 1. This electric welding of the clips and tension wires might be effected in any suitable way, such as for instance, providing a point or projection 4 on the clip 3 as shown in Fig. 5, passing an electric current through the wire and clip and pressing them together in the line of the projection, the weld when finished being shown in Fig. 6. The point at which the clips are preferably welded to the tension wires is indicated at 5.

In the drawing Fig. 1, I show two sections of metal fabric, the intersecting tension wires 1 and distributing wires 2 being secured to each other at their intersec-

tions in any suitable manner. Each section is made up rigid at the factory and complete in itself, the tension and distributing wires being preferably welded to each other at 5 their intersections in any suitable manner. The end tension wires of each section are provided with the clips 3 electrically welded thereto as previously described, the clips being preferably located between the distributing wires of the section, although they might, if desired, be secured to some other part of the wires 1. These sections are shipped in this way, that is with the clips secured to the end tension wires. Each clip 15 is provided with a pair of projecting ears 6 which are preferably the free ends of the strip forming the clip 3.

When it is desired to have a larger area of fabric than is obtained by any one section, 20 two or more sections may be joined together, in the following manner. 7 indicates connecting bars preferably formed of flat material similar to the distributing wires 2, and 8 indicates openings suitably formed in said 25 bars near either end thereof as shown. The ears 6 of the clips 3 pass through the openings 8 in the connecting bars and are turned over against the opposite side of the bars 7, thus holding the tension wires 1 to the bars 30 7, the clips of the tension wire of one section being fastened to the connecting bars 7 at one end and the clips secured to the tension rod of another section being fastened to the connecting bar at the other end, thus joining 35 the two sections together.

When it is desired to provide tension and distributing wires of such size that it would be impractical to ship them securely fastened together as a fabric, the tension wires are 40 each provided with clips 3 electrically welded thereto as previously described and spaced apart the proper distance for the distributing wires to be. The distributing wires are preferably provided with openings 45 similar to the openings 8 in the connecting bars 7 suitably located to receive the ears 6. Thus it will be seen that by so preparing the tension and distributing wires, the same can be easily, and quickly fastened together at 50 their intersections by merely laying the tension and distributing wires over each other in such position that the ears 6 will pass through the openings 8 after which a blow from a hammer will bend them over and 55 clench them against the distributing wire. By so preparing the wires, the workman does not have to properly space the wires as the clips 3 are securely fastened to the tension wires and the openings are definitely 60 located in the distributing wires. Obviously for convenience in shipping, the ears 6 might be bent against the periphery of the wire 1 and readily opened out when desired.

to form the fabric. The fabric is illustrated in Fig. 4.

Preferably the clip 3 is formed as shown more clearly in Fig. 7 from a piece of flat stock and provided with the ears 6 formed on the free ends thereof. The ears 6 are preferably of smaller width than the body of the 70 clip so as to form shoulders 10 which limit the extent that the ears project through the openings 8 and also form abutments against which the ears 6 clamp the connecting bars 75 or distributing wires 2.

In Fig. 8 is illustrated the manner of forming the reinforcement for a concrete column in which the rods 9 corresponding to the tension wires 1 are each provided with clips 3 the ears of which are secured in suitable openings in the bands 7 in a manner as previously described and which in this case are bent in a circular form as shown.

I do not limit myself to the use of clips of the exact form shown but may use other 85 forms which convenience may dictate without departing from the spirit of the invention.

What I claim as my invention is:

1. A metallic fabric comprising individual 90 sections, each made up of intersecting members, fastening clips electrically welded to the end members of each section, and a coupling bar extending between the clips of adjoining sections, said clips having their free 95 ends attached to said coupling bar.

2. In a metal fabric, the combination with a number of sections of fabric consisting of intersecting members, of clips electrically welded to the end members of each section 100 and connecting bars secured to adjoining sections by said clips.

3. In a metal fabric, the combination with a number of sections of fabric consisting of intersecting members, of clips electrically welded to the end members of each section and coupling bars joining the sections together, said clips being provided with means for fastening them to said coupling bars.

4. In a metallic fabric, the combination with a number of sections of fabric consisting of intersecting members, of clips electrically welded to the end members of each section, connecting rods or bars provided with openings therein, and free ends secured to said clips adapted to be clamped to said connecting bars through said openings.

Signed at New York in the county of New York and State of New York this 25th day 120 of January A. D. 1909.

MAURICE LACHMAN.
